BALL ROLLING MACHINE

Fokko H. G. Brandt, and Benjamin E. Bockting,
Kansas City, Mo.

Application August 20, 1934, Serial No. 740,622

8 Claims. (Cl. 80—23)

This invention relates to improvements in ball forming machines distinctly classed in the special rolling mill type and seeks to provide an efficient and economical machine to produce large quantities of balls for various purposes.

An object of the present invention is to provide a machine that will feed bar stock therein measure the length of blank, shear, feed blank into center line of roller dies between the roller dies without the rolling and shearing forces of the roller dies acting thereon, rolling and shearing the rod into balls, said roller dies arranged to continue rolling and perfecting the spherical shape of said balls, and means arranged to feed, hold and discharge the balls from the machine, the roller die bearings being held in a singularly adjusted fixed position during the entire cycle of operation.

Heretofore a machine has been invented to roll blanks into balls by manually feeding blanks to the roller dies but the roller dies are spread apart to receive the blank before rolling and the rolls are gradually moved together during the rolling operation. The greatest force in any rolling machine is the force required to hold the roller dies together during the reducing or rolling operation. The force to hold the roller dies together is usually several times greater than the rolling force required to turn the roller dies, and it can be easily seen that the prior machine with movable rolls during the rolling operation will consume at least several times the power required to roll the bar into balls in the present invention.

One of many objects of the present invention is to project every other cutting edge on the roller dies beyond the remaining cutting edges to eliminate polar or severing marks.

Another object of the present invention is to provide upper and lower frames to the ball rolling machine. The lower bed frame receives the bearings for the roller die journals and connections for the upper frame. The upper frame has the feeding mechanism, shearing mechanism and adjusting means for the journal bearings mounted thereon and several bolts hold the lower and upper frames together. When it is desired to remove or change the roller dies the several bolts are removed and the upper frame with its mechanisms mounted thereon is removed by an overhead crane leaving the lower bed frame, journal bearings, roll feeder and roller dies for easy access.

Another object of the present invention is to adjust the roller dies by lateral and longitudinal means so arranged that when the upper and low-

er frame come together the journal bearings will automatically align themselves, there being only a slight adjustment required thereafter to take care of worn roller dies or different pairs of roller dies.

A still further object of the present invention comprises a frame, automatic means arranged on the frame to feed bar stock to the machine, automatic means arranged on the frame to shear said stock into blanks, automatic means on the frame to shear and roll each blank into multiple balls, and means arranged to continue rolling and perfecting the spherical shape of said balls.

With these and other objects in view the invention further consists in many combinations and arrangements of new and old parts illustrated in the accompanying drawings, described in the specifications, and more particularly pointed out in the appended claims.

In the drawings:

Figure 1 is a plan of the improved ball rolling machine illustrating the fragment of a motor and gearing mechanism connected to the ball rolling machine by means of flexible shafts to the roller die shafts.

Figure 2 is an enlarged longitudinal view of the improved ball rolling machine in elevation illustrating more particularly the side feeding and shearing mechanism.

Figure 3 is an enlarged lateral broken fragmentary view through the ball rolling machine illustrating more particularly the feeding and shearing mechanism.

Figure 4 is an enlarged lateral broken fragmentary view through the ball rolling machine illustrating the cross-head and feed rod mechanism for feeding the rod blank into the roller dies and extracting the balls. The feed rods being shown with the balls on center line of rolls.

Figure 5 is an enlarged fragmentary broken view through the roller dies illustrating the cross-head in the raised position receiving a rod to be fed to the roller dies. The cam, lever and link being shown in their corresponding positions.

Figure 6 is a view similar to Figure 5 with more detail illustrating the frame and spring to return the crosshead to the upper position when the cam permits. The feed rods are shown with the rod blank in the center line of the rolls, the rolls being shaped to receive the rod blank free from rolling and shearing forces. It is obvious that when the rolls rotate in the same direction that the rod will be sheared and shaped to form balls.

Figure 7 is a view similar to Figure 5 illustrating the balls being discharged from the feed rods.

The cam, lever, link and crossheads being in their respective positions.

Figure 8 is an enlarged longitudinal view in elevation of the main driving gears, the driving pinion shaft being shown broken to illustrate.

Figure 9 is an enlarged view of the brake or tension member to prevent idling movement of the feed rolls. The shaft and frame being shown broken to illustrate.

10 Figure 10 is an enlarged view of the ratchet driving mechanism for driving the feed rolls. The shaft being shown broken to illustrate.

15 Figure 11 is a still further enlarged broken fragmentary view of the cutting and rolling surfaces of the rolls, illustrating the shape and every other cutting edge projecting beyond the remaining cutting edges.

20 Figure 12 is a still further enlarged broken fragmentary view of the roller die adjustment between bearings.

25 The motor 1 is preferably connected to a standard gear reducer 2 by means of a coupling 3 to reduce the speed of the coupling 4 to where it can be conveniently transmitted to the pinion 5 through shaft 6, the shaft 6 being held in frame 7 by means of bearings 8. The pinion 5 is arranged to drive two gears 9 in the same direction which in turn are mounted on duplicate shafts 10 journaled in bearings 11. A gear 12 driven from one of the gears 9 is mounted on the shaft 13 journaled in the bearings 14 on the frame 7.

30 Couplings 15 mounted on shafts 10 are bolted to flexible shafts 16 at 17 which in turn are bolted at 20 to couplings 18 mounted on roller die shaft trunnions 19. Coupling 20 mounted on shaft 13 drives shaft 21 which is connected to the cam shaft 22 through the coupling 23. The grooves 24 and 25 cut in the shafts 21 and 26 are arranged to cause the shafts to break at the grooves in case an over load is forced upon the roller dies 27. 40 The short shafts 26 can easily be replaced by disconnecting couplings 28 and will prevent breakage on more expensive parts of the machinery. Likewise shaft 21 can be easily replaced by means of the couplings 20 and 23.

45 The lower bed frame consists of two box shaped rails 29 bolted to floor channel irons 30 at 31, the channels usually being set in a concrete floor or base. A vertical square pocket 32 is located in rails 29 near each end thereof, and receives the vertical frame posts 33 bolted therein by bolts 34. The four posts 33 continue upward to the upper longitudinal frame members 35 and are preferably integral therewith. Two of the posts 33 are integrally connected together by means of 50 the I beam shaped member 36 while the members 35 are integrally connected by box shaped cross members 37 and 38.

55 Between the upper frame members 35 and lower frame members 29 are bearing slide box segments 39 and 40 provided with bushings 40' and 41 having integral collars 42 and 43, the bearing box segments being held against outward movement by lips 44, and inward movement prevented by collars 42 and 43 bearing against the roller die shafts 45 and roller die hubs 46. The roller die hubs bear against integral shaft collars 47 and are fitted in the bushings 40' and 41.

60 Through the bearing box segments 39 are threaded adjusting screws 50 with lock nuts 51 to move the bushings 40' and collars 42 for the purpose of aligning the roller dies and fitting them against lateral movement. Longitudinal adjusting movements of the bearing box segments are made through the sloping sides 52 and 53, wedges 54 and 55, posts 33 and adjusting screws 56 with

their lock nuts and grooves 58. The grooved portion 58 fits in the narrow portion of inverted T slots 59 while the lower end of the screws 56 fit the wide part of the slots. Grooves 60 and 61 receive slide bars 62 and 63 integral with slides 54 and 55 respectively.

65 The upper crosshead 64 is bolted to the lower crosshead 65 by integral ears 66 and 67 respectively and bolts 68. The two crossheads are provided with feed rods 69 and 70 set screwed at 71 and 72 into holes bored in the crossheads. The feed rods project from the crossheads toward each other and pass between the roller dies 27, there being space enough therebetween to freely receive blanks and move the typical blank 13 or 15 balls 74 with the crosshead. The lower feed rods 70 have their upper or feed ends 75 thereof sloping enough to cause the balls to feed to one side of the crosshead and discharge into a conveyor trough 76 leading from the machine. The upper 20 crosshead 64 is slidably arranged between frame members 35 and is guided in place by integral guide bars 77 while the lower crosshead 65 is slidably arranged between frame members 29 and guided in place by integral guide bars 78. The 25 floor or sub-base pit 79 is arranged to receive the projecting end of the lower crosshead, and the upper crosshead 64 is provided with integral ears 80 fitted with the lower end of the link bars 81 fulcrumed on bolts 82.

30 The rocker arms 83 and 83a are provided with bosses 84 and mounted on rocker shaft 85, the outer ends of the arms receive the upper fulcrumed ends of link bars 81 bolted at 86, the central outer portion of arm 83 being provided with integral guide bars 87 and shearing die 88 bolted at 89. Integral with and on the opposite side of bosses 84 are a pair of cam levers 90 provided with cam rollers 91 journaled on bolts 92. The rocker shaft is journaled in bearings 93 bolted at 94 and the bosses 84 bear against the inner 40 edges thereof. A die 95 is set in one of the frame members 35 at 96 and held in place by bolts 97.

45 Shaft 22 is journaled in bearings 98 and 99 and has keyed thereon cams 100 bearing against the inner faces of bearings 98 and 99 and are held by 50 keys 101. These cams operate cam rollers, cam levers, rocker arms, shears and crossheads at predetermined degrees of a cycle of operation, the cam revolutions being the same as roller die revolutions. The cams 100 are each provided with 55 a projecting tooth 100a to cause the arms to lower the crosshead below center line of roller dies to discharge finished balls and at the same time shear the stock bars into blanks. Each cam is also provided with a recess 100b to cause the 55 crosshead to raise above center line at roller dies and receive the blanks. On one end of shaft 22 is keyed a hub 102 of crank arm 103 and to the side of the crank arm are two holes positioned at 104 to represent adjustment of the universal 60 joint 105 shown connected to the position farthest from the shaft. The socket portion of the universal joint is integral with the socket portion of another universal joint 106 at the lower end of ratchet connecting rod 107 fulcrumed at 108 in 65 levers 109 pivoted on ratchet wheel 110. The levers 109 have adjusting holes 111 therein and a pawl 112 pivoted at 113 counter-weighted with integral arm 114.

70 The ratchet wheel 110 is keyed on the shaft 115 70 journaled in the bearings 116 and 117 and drives the bevel gear 118 also keyed to shaft 115. Between the ratchet wheel and the bearing 117 a drum 119 is keyed to the shaft 115 and its freedom of movement is controlled by a friction band 75

120 bolted to the arm 121 of frame post 33. The tension of the band is controlled by spring 122, bolt 123, and lock nuts 124. The bearing 116 is integrally connected to one of the posts 33 at 125 5 while the bearing 117 is integrally connected to a frame 126 bolted to one upper frame member 35 and one lower frame member 29.

The friction feed rolls 127 and 128 are secured to the top of the shafts 129 and 130 respectively 10 by bolts 131 and washers 132 and the rollers are aligned to feed bar stock into the quill 133, shear dies 88 and 95 and pass the end of the bar stock to the adjustable stop 134 keyed to the rocker shaft 85 and held in place by set screw 135. Integral 15 with the stop 134 is an eye 136 arranged to receive one end of the coil spring 137 and the opposite end of the coil spring is hooked through a hole 138 in the I beam 36. The rocking gauge stop 134 is a form illustrated for large size rods, 20 however we do not wish to be confined to the specific use thereof and an adjustable fixed stop not illustrated may be used on the frame 35 in its place especially for very small rods without departure from the present invention.

25 The shaft 129 is journaled in the bearing 139 on the frame member 35 and bearing 140 on frame 126 and is driven by a bevel gear 141 arranged thereon to mesh with bevel gear 148. A spur gear 142 is arranged on the lower end of the shaft 129 and meshes with gear 143 mounted on the lower end of shaft 130. The shaft is slightly pivoted with the bearing 144 at 145 and the gears 142 and 143 are cut and arranged to take care of the slight movement. A sliding bearing 146 is arranged to receive the shaft 130 and is arranged to slide in the guide housing 147 bolted to one of the frames 35.

On one side of the slide bearing 146 is a spring 148, clamp 149, feed screw 150, handle nut 151 40 to adjust the tension of the feed rolls and force the turning rolls to feed the bar stock to the shears and stop. Opposing the spring on the opposite side of the bearing is an eccentric 152 pivoted in the frame 141 at 153 and having an integral lever 154 thereon. The lever is fulcrumed to the rod 155 at 156 to be operated by the foot lever 157 pivoted to one of the lower frame members 29. The foot lever receiving the lower fulcrumed end 158 of rod 155 and is held 45 in the released position shown by the spring 148.

A guide pan 159 is located between the upper frame members 35 and is secured thereto with machine screws 160, the pan formed to guide blanks over one of the roller dies to the feed rods.

50 When it is desired to operate the ball rolling machine the stock bars are first heated to rolling temperature, then fed through the feed rolls, quill, and shears to the gauge stop where it remains until that degree of the cycle of operation 55 is reached to discharge the balls from the rolls, then a blank is automatically sheared from the bar stock. The blank then falls by gravity to the guide pan 159 where it rolls over to the feed rods located between the rolls. The crossheads and feed rods then raise to the position shown in Figure 5 where the blank starts to enter the space between the feed rods and immediately the crosshead and feed rods move downwardly to the center line of the roller dies as shown in Figure 6, the blank then being on the center line of the roller dies between the roller dies and between the feed rods. The roller dies are cut away at 60 65 70 75 to allow the blank to pass to the center line of the roller dies without the shearing and rolling forces of the roller dies acting thereon.

While the crossheads and feed rods remain in the position shown in Figure 6 the roller dies revolve in the same direction gradually shearing and rolling the blank into multiple balls, the roller dies continue rolling and perfecting the spherical shape of said balls but just before a complete revolution of the rolls takes place the feed rods move downwardly to discharge the balls as shown in Figure 7. The balls roll from the sloped surfaces 76 of the bottom feed rods 70.

It is obvious that the feed rolls feed the bar stock during one half of a cycle of operation by reason of the crank 103 and the ratchet wheel 110. The ratchet turns a quarter of a revolution to one half revolution of the cam shaft. The bevel gears 148 and 141 are approximately proportioned to give the feed rolls the desired length of feed. When it is desired to stop the feed of bar stock without stopping the machine from operating, the operator places his foot on the foot lever 157 and releases the spring tension on the feed rolls. The friction band 120 prevents idling of the feed rolls immediately after each ratchet feed. Feed roll 128 is driven through the spur gears 140 and 143.

When it is desired to change rolls the four bolts 34 in the frame members 33 and 29, two bolts 86 in rocker arm links, and four bolts 162 in frame members 29 and 126 are removed. An over-head crane is fastened to the upper frame members by means of a chain not shown and the crane removes the upper frame with its mechanisms, and lower bed frame and roller die bearing boxes remaining with the crosshead between the roller dies.

By spreading the bearing box segments the roller dies can be easily removed and replaced by the reverse of the operation hereinbefore described. When the upper frame is replaced on the lower frame members it may be necessary to 40 adjust the spacing of the roller dies slightly by the wedges 54 and 55 operated manually through the adjusting screws 86.

The feed rolls are also spread apart by the operator pressing his foot on lever 157 to allow a bar 45 to enter between the rolls or to remove a short or undesirable bar.

What we claim as new and desire to secure by Letters-Patent is:

1. In a ball rolling machine the combination of 50 a frame, a pair of rolls, automatic means arranged on said frame to feed bar stock to said machine parallel to the axis of said rolls, a gauge arranged to gauge the length of said stock, automatic means arranged on said frame to shear said stock 55 into blanks, and automatic means arranged in said frame to shear and roll each blank into multiple balls.

2. In a ball rolling machine the combination of 60 a frame, automatic feeding mechanism arranged to feed bar stock thereto, means arranged on said frame adapted to shear said stock to blanks, a pair of rolling dies arranged to receive therebetween said blanks to the center line of said roller dies without the shearing and rolling forces 65 of said rolls acting thereon, means arranged to shear and roll said blank into balls, said dies arranged to continue rolling and shaping said balls, feeding rods arranged to discharge said balls from said machine, and means to hold the 70 journal bearings of said rolls in a fixed position during the entire cycle of said described operation.

3. In a ball rolling machine the combination of 75 a frame, roller dies arranged in said frame to roll

- and shear a blank into balls, journals integral with said roller dies, slidably arranged bearings in said frame adapted to receive the journals of said roller dies, wedges arranged in said frame 5 to adjust the space between said bearings, automatic means arranged to feed said blanks to the center line of said rolls without the rolling and shearing forces acting thereon, means adapted 10 to roll and shear said blanks into balls, on nearly the entire periphery of said rolls, means arranged to discharge said balls from said roller dies, and said journal bearings held in a fixed position throughout the entire rolling and shearing operations.
- 15 4. In a ball rolling machine the combination of a frame, roller dies arranged in said frame to roll and shear a blank into balls, journals integral with said roller dies, slidably arranged bearings in said frame adapted to receive the journals of 20 said roller dies, adjustable wedges arranged in said frame to adjust the spacing between said bearings, and said bearings arranged in their respectively fixed positions when said roller dies shear and roll said balls.
- 25 5. In a ball rolling machine the combination of a frame, bearings, a pair of roller dies arranged in said bearings to roll and shear a blank into balls, automatic means to feed bar stock to said machine, automatic means to shear said stock 30 into blanks, automatic means connected to and operated by said shearing means to feed said blanks and hold them to the center line of said roller dies, and means to hold said roller die
- bearing in a fixed position during the rolling and shearing of said blanks and balls.
6. In a ball rolling machine comprising a frame, a pair of roller dies mounted therein, an upper and a lower crosshead arranged to slide in said frame at right angles to a center line through said roller dies, feed rods mounted therein to feed blanks to said roller dies, a rocking lever arranged on said frame, a link bar connecting said rocking lever to said upper crosshead, said upper crosshead secured to said lower crosshead, and means to operate said rocking lever.
7. In a ball rolling machine comprising a frame, a pair of roller dies mounted therein, a pair of crossheads arranged to slide in said frame at 15 right angles to a center line through said roller dies, said crossheads bolted together, rods mounted therein to feed blanks to said roller dies, rocking levers arranged on said frame, link bars connecting said rocking levers to only one 20 of said crossheads, and means to operate said rocking levers.
8. In a ball rolling machine the combination of a frame, a pair of roller dies arranged thereon to shear and roll a single blank into multiple 25 balls, said roller dies having every other shearing edge thereof projecting beyond the remaining shearing edges, and said projecting shearing edges of each die fitting said remaining shearing edges of the opposite die. 30
